UNITED STATES PATENT OFFICE.

DAVID BALDWIN PIERSON, OF HARTFORD, CONNECTICUT; MARY N. PIERSON
ADMINISTRATRIX OF SAID DAVID BALDWIN PIERSON, DECEASED.

MILK-BOTTLE CLOSURE AND STOPPER-EXTRACTOR.

1,119,985.

Specification of Letters Patent.

Patented Dec. 8, 1914.

Application filed August 15, 1911. Serial No. 644,121.

To all whom it may concern:

Be it known that I, DAVID BALDWIN PIERSON, a citizen of the United States of America, residing at Hartford, in the county of 5 Hartford and State of Connecticut, have invented new and useful Improvements in Milk-Bottle Closures and Stopper-Extractors, of which the following is a specification, reference being had to the accompanying 10 drawings and letters of reference marked thereon.

The object of my invention is to provide a simple, inexpensive, sanitary and adjustable device for employment with milk bottles with which the usual paper or cardboard stopper may be conveniently removed and the closure device substituted, thus hermetically sealing the bottle, and I accomplish the objects of my invention by the construction herein shown.

In the accompanying drawings, in which like letters of reference indicate like parts, Figure 1 is a side elevation of my device; Fig. 2, a side view in section; Fig. 3, a side 25 view with the parts detached, and Fig. 4, a plan view.

In detail, *a* indicates the lower body portion of the device, *b* the upper body portion, *c* the threaded member by means of which 30 the two are connected, *d* a raised surface, *e* an expansible packing ring, and *f* a hook or pin for the removal of the pasteboard stopper.

The construction of my device will be 35 readily understood on reference to the drawings.

The lower body portion of the device is provided with a downwardly-projecting hook *f* for engagement with the ordinary 40 paper stopper employed in bottles and by which the same may be readily removed. The lower body portion is provided also with an upwardly-projecting threaded member *c* and with a raised portion *d*, the same 45 being raised, however, a distance less than the thickness of the packing ring. The upper body portion *b* is provided with a threaded recess to receive the threaded member *c* of the lower portion, and the 50 packing ring *e* is clamped between the portions of the upper and lower body por-

tions located outside the raised portion *d*. The packing ring preferably consists of pure rubber and its diameter may be varied by compression between the clamping faces 55 sufficiently to cause it to fit tightly in openings of slightly differing diameters by the difference in the extent of compression applied to it by screwing the two body members together more or less tightly, so that 60 if it be found that the ring is loose when applied to a bottle, the two members may be screwed more tightly together, thus compressing the packing ring, causing it to expand slightly, thus increasing its diameter 65 and causing it to fit more tightly in the bottle opening. The upper body member is provided with a convenient knob or handle.

It will readily be seen that in making the device readily separable, that it may be 70 easily cleansed by separating the parts, washing them, and replacing them, so that all danger of contagion resulting from particles of food lodging in crevices of the device may be readily avoided, and that the 75 device may be conveniently separated, cleansed, and reassembled.

Having, therefore, described my invention, what I claim and desire to secure by Letters Patent, is—

A bottle closure of the character specified, comprising superposed upper and lower disk-like body members, the latter of which is provided upon its upper face with a central raised portion and with an upstanding 85 threaded projection located centrally of the same, the upper body member having a threaded recess opening through the center of its under face to receive said projection, a handle provided upon said upper body 90 member, and a yielding packing ring of greater diameter than said members encircling said raised portion and having a thickness greater than the height of such portion, whereby said ring will be compressed when said members are tightened 95 together.

DAVID BALDWIN PIERSON.
